US0D1081454S

(12) United States Design Patent (10) Patent No.: US D1,081,454 S
(45) Date of Patent: * Jul. 1, 2025

(54) CLOUD SHAPED ORNAMENT

(71) Applicant: Enhong Jing, Dongguan (CN)

(72) Inventor: Enhong Jing, Dongguan (CN)

() Term: 15 Years

(21) Appl. No.: 29/987,242

(22) Filed: Jan. 22, 2025

(30) Foreign Application Priority Data

Dec. 31, 2024 (CN) 202430840652.0

(51) LOC (15) Cl. 11-05

(52) U.S. Cl.

USPC D11/125; D11/131; D11/133

(58) Field of Classification Search

USPC D11/30, 44, 48, 81, 99, 117, 125, 131,

D11/132, 133, 141, 142, 149, 157

CPC A63H 27/10; A63H 33/22; A63J 99/00;
F21V 14/04; G09F 19/16
